CYLINDER LOCK

Edward N. Jacobi, Milwaukee, Wis., assignor to
 Briggs & Stratton Corporation, Milwaukee,
 Wis., a corporation of Delaware

Application June 5, 1936, Serial No. 83,674

8 Claims. (Cl. 70—368)

This invention relates to improvements in locks and refers particularly to cylinder locks.

It is an object of this invention to provide an improved and simplified manner of removably securing the cylinder of a lock of the character described in its casing.

More specifically it is an object of this invention to provide a removable cylinder lock in which the cylinder is positively held against withdrawal by means of a bayonet slot connection and in which releasable stop means normally holds the cylinder against rotation to its releasing or withdrawing position.

A further object of this invention is to provide common means for preventing rotation of the cylinder to its withdrawing position and also to define the normal limits of rotation of the cylinder.

A still further object of this invention resides in the provision of a lock of the character described wherein release of the stop means which prevents rotation of the cylinder to its withdrawing position is effected by means of a tool inserted into the lock from the front end thereof.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in which:

Figure 1 is a longitudinal section view through a lock embodying this invention and showing the cylinder in its unlocked position of rotation;

Figure 2 is a cross section view taken through Figure 1 on the plane of the line 2—2;

Figure 3 is a cross section view through Figure 1 on the plane of the line 3—3;

Figure 4 is a view similar to Figure 1, showing the manner in which the cylinder is released for rotation to its withdrawing position; and

Figure 5 is a cross section view similar to Figure 2 but showing the cylinder turned to its withdrawing position.

Referring now more particularly to the accompanying drawings in which like numerals indicate like parts throughout the several views, the numeral 5 designates a mounting member or

casing of the lock which in the present instance is illustrated as the handle of an automobile door. As is customary, the mounting member 5 has a bore 6 to receive a cylinder 7, the cylinder 7 being inserted into the bore through its open front end. The inner end of the cylinder is arranged for driving coaction with an adaptor 8 through which rotation of the cylinder is imparted to the latching mechanism (not shown).

The driving connection between the cylinder 10 and the adaptor 8 comprises an eccentric driving cam 9 projecting from a reduced neck or inner end portion 10 on the cylinder and engaging in a recess 11 in the head of the adaptor 8. This connection permits the cylinder to be withdrawn 15 without disturbing the adaptor.

The casing or mounting member 5 has two diametrically opposed longitudinal tumbler receiving grooves 12 and 13 extending in from a counterbore 14 in the front end of the casing. 20 The groove 12 extends to the extreme bottom of the bore 6, but the groove 13 is considerably shorter.

Mounted in the cylinder are the usual locking tumblers 15 which are projectable into the tumbler receiving groove 13 to secure the cylinder against rotation in a locked position and projectable into the long tumbler groove 12 during insertion and removal of a key 16 used to retract the tumblers and free the cylinder for rotation. 30

The cylinder is removably secured in the bore 6 by a bayonet slot connection with the casing at the mouth of the bore 6 comprising two circumferentially aligned lugs 17 on the cylinder at a slight distance inwardly from its outer head 18 35 which lugs engage in back of an arcuate ledge 19 projecting in from the counterbore 14 and extending circumferentially from one edge of the groove 12 to the adjacent edge of the groove 13.

The lugs 17 are so disposed circumferentially 40 with respect to the arcuate length of the ledge 19 that during the normal rotation of the cylinder between locked and unlocked positions, which requires one hundred and eighty degrees, one of the lugs 17 is at all times in back of the ledge 19 45 19 thus positively retaining the cylinder against withdrawal. Withdrawal of the cylinder is possible only upon rotation of the cylinder beyond its unlocked position a distance sufficient to carry both of its lugs 17 out of alignment with the 50 ledge 19.

Rotation of the cylinder to this withdrawing position is normally prevented by a stop washer 20 non-rotatably held in the bore of the casing and engageable with a stop lug 21 projecting 55

from the side of the reduced neck or projection 10 on the inner end of the cylinder for defining the normal limits of rotation of the cylinder.

The washer 20 has an outer diameter substantially equal to that of the cylinder so as to be slidably disposed in the bore 6 and its bore 22 is of such size as to accommodate the reduced neck or projection 10. Throughout its major circumference, the bore 22 in the washer is enlarged as 10 at 23 to accommodate the stop lug 21 on the cylinder, the termini of the enlarged portion 23 providing abutments 24 engageable by the lug 21 to normally limit the rotation of the cylinder to one hundred and eighty degrees.

15 The washer is held against rotation with respect to the casing by two outwardly projecting ears or lugs 25 and 26 which are received in the long tumbler groove 12, and a third longitudinal groove 27, respectively, formed in the casing 5 in 20 communication with its bore. This manner of securing the stop washer against rotation, however, does not interfere with flatwise movement thereof along the axis of the lock, and to hold the stop washer in its normal operative position 25 engaging the inner end of the cylinder, a compression spring 30 is confined between it and the adaptor 8.

As long as the stop washer is retained in this 30 normal position engaging the inner end of the cylinder, the stop lug 21 coacting with the abutments 24 on the stop washer restricts the rotation of the cylinder to the one hundred and eighty degrees comprising its normal range of motion.

However, upon rearward displacement of the 35 stop washer, as shown in Figure 4 to dispose the same rearwardly of the lug 21, rotation of the cylinder beyond its normal limits is permitted. Such rearward displacement of the stop washer may be effected by means of a tool 33. The tool 40 33 comprises a wire stem having a head 34 arranged to overlie the flat head of the key 16. In using the tool 33, it is inserted through a recess 35 in the edge of the cylinder head 18 which aligns with the longitudinal groove 27 when the 45 cylinder is in its unlocked position of rotation until its inner end strikes the lug 26 on the washer and thereby pushes the washer back. The head 34 on the tool overlies the key in this 50 position which makes it easy to retain the releasing tool in inwardly pressed position and simultaneously turn the cylinder.

It will be noted from Figure 2 that the notch or recess 35, the bottom of which dips down beneath the cylindrical surface of the cylinder 55 proper a slight distance, is located adjacent one side edge of the longitudinal groove 27 when the cylinder is in its unlocked position of rotation. Consequently, it is possible to turn the cylinder with the tool 33 in place a distance sufficient to 60 carry the lug 21 past the adjacent abutment 24, after which the lug 21 holds the stop washer in its displaced position so that the tool may be withdrawn and the cylinder turned the required number of degrees to carry both of its lugs 17 65 out of locking engagement with the ledge 19.

As noted hereinbefore, when the cylinder has been turned to a position, such as shown in Figure 5 at which both of its lugs 17 are disengaged from behind the ledge 19, the cylinder is free for 70 withdrawal.

To insert the cylinder, it is only necessary to press the same inwardly against the action of the spring 30 until its lugs 17 are disposed inwardly of the ledge 19 whereupon the cylinder may be 75 turned clockwise to carry the lugs 17 in back

of the ledge 19 and dispose its stop lug 21 in the enlargement 23 of the stop washer.

From the foregoing description taken in connection with the accompanying drawings, it will be readily apparent to those skilled in the art to which this invention appertains, that this invention provides an exceptionally simple and efficient manner of removably securing a lock cylinder in place.

What I claim as my invention is:

1. In a lock, a bored casing, a lock cylinder rotatably mounted therein, means for positively holding the cylinder against withdrawal from the casing bore except in a predetermined position of rotation, and means for normally preventing rotation of the cylinder to said position comprising an eccentric stop lug projecting from the inner end of the cylinder, a stop washer non-rotatably held in the casing bore and engaging the inner end of the cylinder, said stop washer having an arcuate passage to accommodate the eccentric stop lug, the ends of said arcuate passage forming an abutment engageable with the eccentric stop lug to define the normal limits of rotation of the cylinder, and a spring for holding the stop washer in its positive position engaging the inner end of the cylinder while allowing inward displacement of the stop washer beyond the end of the eccentric lug to free the cylinder for rotation to said predetermined position at which it may be withdrawn from the casing bore.

2. In a lock, a bored casing, a lock cylinder rotatable therein, and means to define the normal rotation of the cylinder comprising an eccentric lug projecting from the inner end of the cylinder, a stop washer having an arcuate passage in which the eccentric lug is received, the ends of said arcuate passage forming abutments engageable by the eccentric lug, means for holding said stop washer against rotation with respect to the casing, and yieldable means for holding the stop washer in cooperative relationship with the eccentric lug while permitting the displacement of the stop washer out of cooperative relationship with the eccentric lug.

3. In a lock, a bored casing, a lock cylinder non-rotatable therein, and means for defining the normal limits of rotation of the cylinder comprising a stop member non-rotatably held in the casing bore and engaged with the inner end of the cylinder, means on the cylinder cooperative with the stop washer as long as the stop washer is engaged with the inner end of the cylinder, and spring means for holding the stop washer against the inner end of the cylinder while permitting displacement thereof to an inoperative position freeing the cylinder for rotation beyond one of its normal limits.

4. In a lock, a bored casing having a longitudinal groove communicating with its bore and opening to the front end thereof, a lock cylinder rotatable in the bore, and means for defining the normal limits of rotation of the cylinder comprising a stop member slidably in the casing bore inwardly of the cylinder and having circumferentially spaced abutments, an eccentric lug on the inner end of the cylinder engageable with said abutments as long as the stop member is in a predetermined operative position from which it is movable axially into the bore of the casing, spring means opposing such inward movement of the stop member and holding the same in an operative position, and a lug on the stop member slidably disposed in said longitudinal groove for holding the stop member against rotation in the

casing bore, said last named lug being engageable by a releasing tool inserted into the longitudinal groove from the front end of the lock to enable displacement of the stop member from its operative position.

5. In a lock, a bored casing, a lock cylinder rotatable therein and provided with a head at its outer end, the head having an opening therethrough and the casing having a longitudinal groove opening to its bore with its front end arranged to be covered by the head of the cylinder and to be accessible through said opening in the cylinder head upon alignment of the opening therewith, and means to define the normal limits 10 of rotation of the cylinder comprising a stop washer slidable in the casing bore inwardly of the cylinder and having an arcuate passage with the ends thereof forming stop abutments, an eccentric lug projecting from the cylinder inner 15 end into said arcuate passage to cooperate with the abutments on the stop washer as long as the washer is held against the inner end of the cylinder, a spring holding the stop washer against the inner end of the cylinder, and a lug projecting 20 out from the stop washer and slidably disposed in the longitudinal groove to hold the stop washer against rotation and to provide means engageable by a tool inserted through the opening in the cylinder head and the longitudinal groove 25 for displacing said stop washer inwardly beyond the eccentric lug to thereby free the cylinder for rotation past one of its normal limits.

6. In a lock, a bored casing, a lock cylinder mounted therein for rotation between predetermined limits of normal operation, said cylinder having an enlarged head provided with a circumferential groove accessible from the underside of the enlarged head, means for removably holding the cylinder in the casing including a projection 40 extending from the casing into said circumferential groove, said projection being disengageable

from the groove upon rotation of the cylinder beyond one of its normal limits of rotation, means for defining the normal limits of rotation of the cylinder, comprising a stop abutment on the cylinder and an axially movable non-rotatable plate 5 yieldingly retained in an operative position at the inner end of the cylinder to be engageable by said cylinder carried stop abutment, said plate being accessible for movement out of the path 10 of the cylinder carried stop abutment in the unlocked position of rotation of the cylinder.

7. In a lock, a bored casing, a lock cylinder mounted therein for rotation between normal limits of operation, means for defining said limits comprising stop abutments on the cylinder and 15 a stop member splined to the casing for axial movement and arranged to engage said stop abutments in one position of axial movement and to be freed from engagement with said stop abutments in another axial position, said splined 20 member being protected against access except in one position of rotation of the lock cylinder, and a bayonet joint between the lock cylinder and casing to retain the cylinder against withdrawal 25 from the casing except in a position of rotation beyond the normal limits of rotation.

8. In a lock, a bored casing having a slot extending along the bore, a lock cylinder rotatably mounted therein and axially removable from the bore, tumblers carried by the cylinder and engageable in said slot, bayonet joint means for retaining the cylinder against withdrawal except when the cylinder is in a predetermined position of rotation, a member connected to said casing by a spline joint in said slot, abutments on said 35 member, and abutments on the cylinder engageable with the abutments of said member to prevent rotation of the cylinder to said predetermined position, said abutments being disengageable by axial movement of said member. 40

EDWARD N. JACOBI.
